UNITED STATES PATENT OFFICE.

FRANK W. GRISWOLD, OF MINNEAPOLIS, MINNESOTA.

DESIGN FOR A TRAFFIC SEMAPHORE.

Application filed March 5, 1924. Serial No. 8,840. Term of patent 14 years.

To all whom it may concern:

Be it known that I, FRANK W. GRISWOLD, a citizen of the United States, residing at Minneapolis, in the county of Hennepin and State of Minnesota, have invented a new, original, and ornamental Design for a Traffic Semaphore, of which the following is a specification, reference being had to the accompanying drawing, forming part thereof, and in which,

Fig. 1 is a view in elevation of the device as it appears with the upper part illuminated;

Fig. 2 is a top plan view of the device the color being indicated by the shading in all of said views.

What I claim is:

The ornamental design for a traffic semaphore, as shown.

FRANK W. GRISWOLD.
